UNITED STATES PATENT OFFICE.

FREDERICK B. MILLER, OF SCOTTDALE, PENNSYLVANIA.

SCREEN-FABRICATING MACHINE.

Application filed January 17, 1921. Serial No. 437,924.

To all whom it may concern:

Be it known that I, FREDERICK B. MILLER, a citizen of the United States, residing at Scottdale, in the county of Westmoreland and State of Pennsylvania, have invented certain new and useful Improvements in Screen-Fabricating Machines, of which the following is a full, clear, and exact specification.

10 My invention relates to improvements in screen-fabricating machines in which parallel rotating shafts have a plurality of rolls operating in conjunction with a carriage for interlocking warp members with weft members; and the objects of my improvements are, first, to provide two parallel shafts having a plurality of rolls arranged for bending adjacent warp members oppositely; second, to provide a constant feed 20 for a carriage to operate in conjunction with a staggered arrangement of rolls secured to rotating parallel shafts; and third, rolls are provided to reduce friction at point of contact with the warp members.

25 Fig. 1, is a plan view of a fabricated screen.

Fig. 2, is an end view of fabricated screen.

Fig. 3, is a longitudinal sectional view of the machine taken in the plane of line 2—2 30 of Fig. 4, showing screen secured in carriage, which operates in conjunction with the revolving rolls for interlocking warp members with weft members.

Fig. 4, is an end elevation of the machine embodying my invention.

Fig. 5, is an elevation of shafts, gears and rolls, by means of which adjacent warp members are bent opposite.

Fig. 6, is an end view of shafts, gears and rolls.

The various novel features of my invention will be apparent from the description and drawings, and will be particularly pointed out in the appended claims.

45 While this invention finds application to machines for fabricating screen, the invention is not limited to such machines and to such fabrication.

The bed 10, and the journal frames 11 50 secured to the bed, constitute the frame work of the machine. In the journal frames 11, the shafts 12 13 turn in opposite direction by reason of the gears 14 14. The shafts 12 13 rotated by the gear-wheel 15 are provided 55 with a plurality of rolls 16, arranged on the said shafts, so that the rolls on the

shaft 12 will pass between the rolls on the shaft 13. The basal carriage 17, fed by the screws 18 18 is provided with bearing surfaces 19 19, adapted to slide on guides 20 20. The screws 18 18 turned by the shaft 13, by means of the sprockets 21 22, chain 23, shafts 24 and gears 25 26, are provided thrust bearing surfaces 27 27 and bearings 28 28, so that the screws 18 18 threaded for 60 the reception of the female screws 29 29 in carriage 17, will move the said carriage on the guides 20 20. The carriage 17 has a depression 30 for proper alignment of the warp members 31, which are secured to the 65 carriage by a clamp bar 32 and clamp screws 33 33.

From the construction and arrangements of parts shown and described, it is obvious that the adjacent warp members 31 are bent 70 oppositely sufficiently by reason of contact with the revolving rolls 16, to form a shed to receive a weft member 34. The carriage having advanced one crimp of the longitudinal rod 31, the following rolls 16 come 75 in contact, and bend the warp members, interlocking a weft member with warp members. The operation is repeated to make up the weft members of the screen.

There may be many modifications of the 80 invention other than here shown and described and it is my intention to cover all such modifications which do not involve a departure from the spirit and scope of my invention as set forth in the appended 85 claims.

What I claim as new is:

1. In a machine of the character described, a bed, journal frames secured to said bed, parallel shafts mounted in said journal frames, rolls on one shaft eccentric with respect to said shaft and alternately disposed in opposite directions to roll alternate warp members, rolls on the other shaft eccentric with respect to said shaft and alternately 100 disposed in opposite directions, said rolls staggered with respect to the rolls on the first mentioned shaft to roll alternate warp members from the opposite side, said rolls adapted to revolve in opposite directions to 105 effect bending of adjacent warp members in opposite directions to form a shed to receive weft members, feeding mechanism associated with the rolls for advancing the warp members in step with said rolls.

2. In a machine of the character described, parallel shafts between which warp members

are fed, rolls on one shaft eccentric with respect to said shaft and alternately disposed in opposite directions to engage alternate warp members, rolls on the other shaft 5 eccentric with respect to said shaft and alternately disposed in opposite directions, said rolls staggered with respect to the rolls on the first mentioned shaft to engage alternate warp members from the opposite side, 10 said rolls adapted to roll warp members to effect bending of adjacent warp members in opposite directions to form a shed to receive weft members, feeding mechanism associated with the rolls for advancing the 15 warp members in step with said rolls, in-

cluding a sprocket fixed to one of said parallel shafts, a jack-shaft, a sprocket fixed to said jack-shaft, a chain connecting said sprockets, a screw-shaft, a pair of engaged miter-gears fixed to said screw-shaft and said 20 jack-shaft, a carriage actuated by said screw-shaft, and a clamp bar for clamping the fabric to the carriage.

In testimony whereof I affix my signature, in the presence of two witnesses.

FREDERICK B. MILLER.
